UNITED STATES PATENT OFFICE.

FRED W. FAY, OF WELLSVILLE, NEW YORK.

DESIGN FOR A COMBINED SHADE AND CURTAIN-POLE HOLDER.

43,140.

Specification for Design.

Patented Oct. 15, 1912.

Application filed July 2, 1912. Serial No. 707,356. Term of patent 14 years.

To all whom it may concern:

Be it known that I, FRED W. FAY, a citizen of the United States, residing at Wellsville, in the county of Allegany and State of New York, have invented a new, original, and ornamental Design for a Combined Shade and Curtain-Pole Holder, of which the following is a specification, reference being had to the accompanying drawing, forming part thereof.

The figure is a perspective view of my combined shade and curtain pole holder.

I claim:

The ornamental design for a combined shade and curtain pole holder, as shown.

FRED W. FAY.

Witnesses:

ROBERT F. PECK,
W. F. SMITH.
